SAILBOAT

Gary W. Mull, 6677 Gunn Drive,
Oakland, Calif. 94611

Filed Mar. 6, 1968, Ser. No. 10,867

Term of patent 14 years

Int. Cl. D12—06

U.S. Cl. D71—1

FIG. 1

FIG. 1 is a side elevational view of sailboat showing my new design;

FIG. 2 is a top plan view of the hull of said sailboat with mast, sails, and associated elements deleted for ease of illustration;

FIG. 3 is a rear elevational view of the hull of said sailboat with mast, sails, and associated elements deleted for ease of illustration; and

FIG. 4 is a front elevational view of the hull of said sailboat with mast, sails, and associated elements deleted for ease of illustration.

I claim:

The ornamental design for a sailboat, substantially as shown and described.
